PREPARATION OF DRY SAND MOLDS

Arthur S. Nichols, Oak Park, Ill., assignor to The Illinois Clay Products Company, Joliet, Ill., a corporation of Illinois

Application April 2, 1943, Serial No. 481,555

2 Claims. (Cl. 22—192)

This invention relates to metal founding, and among other objects aims to improve the method of making dry sand molds, cores, and the like.

The nature of the invention may be readily understood by reference to illustrative embodiments thereof hereinafter described.

In the drawing:

Fig. 1 is a diagram, partly in section, illustrating one method of conditioning a mold; and

Fig. 2 is a diagram similar to Fig. 1 wherein different means for practicing the method are employed.

Generally sand used for making molds and cores in the founding of metals, both ferrous and non-ferrous, including iron, steel, aluminum, magnesium, etc., and various alloys of the same, is composed of sand grains combined with either a natural or an added clay bond, organic bonding agents, oils, sea-coal, etc., or a mixture thereof. In preparation for molding the sand and added ingredients are mixed or mulled together, and tempered with water or with an aqueous liquid binder.

The sand when molded is in the green condition and frequently receives the molten metal without other treatment. While green sand is permeable to air and gases, the permeability to the free passage of gases generated by the pouring of the metal is low compared to a dry sand mold because the tempering moisture assists in partially filling the free pore space. Increasing permeability in a green sand mold sometimes requires costly expenditures for more concentrated bonds or specially selected sand grains to make the sand more open.

Drying substantially increases permeability. For example, one mixture having a green sand permeability of 70 has a dry sand permeability of 170. The green sand strength is likewise low, and in this condition the sand is generally too weak for handling in the form of cores which are molded separately from the mold itself and inserted therein after the mold is formed. The green sand mold is frequently below the strength necessary to give a smooth finish, free from defects, on the surface of the casting and the cost of cleaning and finishing such castings is high.

Drying substantially increases strength. For example, one mixture having a green compression strength of ten pounds per square inch develops on drying a compression strength of seventy-five pounds per square inch.

Heretofore the green sand mold surface was sometimes made stronger by skin drying, with a torch, but in many types of casting production

the entire mold is dried in an oven before being used in the casting operation. The cores are almost invariably oven dried or baked before being inserted in the mold. This drying process is expensive and, depending upon the size of the mold or core, takes considerable time. Considerable equipment is tied up and additional fuel and manpower needed.

10 I have discovered a method of conditioning molds and cores in a very short time, so short indeed that special handling or diversion from the production line is reduced or eliminated.

15 In the practice of my process I conduct air to the mold or core and cause it to pass through the permeable sand and thereby carry off the moisture to produce a strong dry sand mold or core in a matter of seconds or minutes. In some cases the conditioning action of the air is not merely one of drying as where strength depends 20 on oxidation of the bonding agent.

25 Preferably the air is passed from the mold or core face outwardly through the sand. This has the advantage of drying the most important part first and if for any reason complete drying is unnecessary, that part to be nearest the molten metal will have been dried in a minimum time.

Drying may be accelerated by heating the air, or by drying the air, or by using heated dried 30 air. Any appropriate method of drying or heating the air may be used. One inexpensive method of drying requiring little equipment is to pass the air through a hygroscopic substance such as fuller's earth or southern montmorillonite, both 35 or which are relatively inexpensive as compared to the chemical type of hygroscopic substances. The efficiency of these substances can be quickly and repeatedly restored by periodically passing highly heated air through the body of the material to carry off the absorbed moisture.

40 One method of introducing the air into the sand is to pass the air through the pattern while it is still against the mold or core face. For this purpose the pattern is provided with passages and 45 perforations or slit-like openings which distribute the air efficiently over the face of the mold or core. Where the thickness of the sand is not excessive or the permeability too low, drying may be effected so quickly as not substantially to retard reuse of the pattern.

50 If the mold is removed from the pattern before drying, the air may be introduced by applying a tightly fitting hood or cover over the flask containing the sand, to deliver the air to the face of the mold, from where it permeates and passes

through the sand, escaping with the collected moisture through the outside of the mold.

If it be impracticable for any reason to introduce the conditioning air at the mold face, it may be introduced at a side or sides of the mold and pass through the mold to escape on the opposite side or sides or where ever escape be possible. The pattern may or may not be removed depending on the nature of the mold and character of the pattern. This method would apply to many types of cores wherein the body to be conditioned is surrounded by the core box or pattern.

The action of the air in changing the sand from the green to the dry condition in instances where an oil type binder is used, as in most cores, and some molds, is not merely one of moisture removal, but involves an oxidation or setting of the binder. Where development of strength depends on something more than mere drying, and as by oxidation of oils, the air should preferably be heated.

The drawing illustrates two methods of conditioning a sand mold. In Fig. 1 a distributing hood or manifold 10 is applied to a flask after the pattern has been removed. Air delivered by the blower 11 is properly conditioned by drying or, as here shown, by passing it through a heater 12, and then it is delivered by conduit 13. The air first strikes the molding face 14 of sand, drying it first and then passes through the body of the sand conditioning it by drying it and/or oxidizing any organic binder therein and then emerges through a remote face of the mold. In the present case the support 15 on which the flask rests is perforated as at 16 to facilitate the escape of the air.

In Fig. 2 conditioning of the mold is effected before the pattern has been withdrawn. As there shown the pattern is provided with a series of perforations or ducts 17 adapted to convey air through the pattern and deliver it to the molding race 18 of the mold from which it passes through the sand, conditioning the sand as in the method illustrated in Fig. 1, escaping through the opposite face 19 of the mold. In the present instance the ducts 17 through the pattern are relatively large and contain terminal vents 20 having a plurality of smaller holes so as to distribute the air more uniformly.

A manifold 22 similar to that employed in the

case of Fig. 1 and which may either be a part of the pattern or separate therefrom distributes the conditioned air from the conduit 23 to the respective ducts 17 in the pattern. The air is conditioned and delivered by a fan 11 and conditioner 12 as in the case of the method illustrated in Fig. 1. After conditioning of the mold the pattern is then withdrawn.

The illustrative method completely revolutionizes foundry practice where sand molds are involved. It permits the use of the stronger and more permeable dry sand mold where it has heretofore been economically and physically unsuitable. It reduces the time of the molding operation where dry sand molds are necessary, and it simplifies core making. It completely eliminates drying and baking ovens and the separate handling of the molds or cores into and out of these structures. It frees tremendous amounts of flask and conveying equipment formerly tied up in the drying operation, and liberates the great area of floor space formerly required for the accumulation of molds and drying ovens.

Obviously the invention is not limited to the details of the illustrative embodiments of the invention herein described since these may be variously modified. Moreover it is not indispensable that all features of the invention be used conjointly since various features may be used to advantage in different combinations and sub-combinations.

Having described my invention, I claim:

1. The method of preparing dry sand molds which is characterized by introducing drying air through openings in the pattern while in the mold to distribute the air over the mold face and causing currents of air to pass through the sand in the mold from the mold face outwardly until the currents of air have carried away enough moisture to develop dry sand strength in the mold, then removing the pattern from the mold.

2. The method of preparing dry sand molds which is characterized by passing air currents through the sand in the mold from the mold face outwardly while the pattern remains in the mold, and continuing said air currents until the air has carried off enough moisture to convert the mold to dry sand condition, and then separating the pattern and the mold.

ARTHUR S. NICHOLS.
